UNITED STATES PATENT OFFICE.

JULIUS L. CABLE, OF BOSTON, MASSACHUSETTS.

FOLDING COT.

Application filed January 28, 1924. Serial No. 688,934.

To all whom it may concern:

Be it known that I, JULIUS L. CABLE, a citizen of the United States, a resident of Boston, in the county of Suffolk and State 5 of Massachusetts, have invented an Improvement in Folding Cots, of which the following is a specification.

This invention relates to folding cots of the type ordinarily used for camping and 10 which usually comprise a stout canvas stretched on a frame.

Cots of this type have usually been constructed of strips of wood connected by hinges and the primary object of my invention is to provide an improved form of 15 folding cot which may be made of semi-tubular metal and which will have substantially greater strength and durability than the wooden frame cots, and is adapted to be 20 compactly folded.

Other objects of my invention are to provide a form of frame for a folding cot which may be constructed of sections of semi-tubular metal which are jointed together in 25 a manner to give ample rigidity at a satisfactory manufacturing cost.

I accomplish these objects in the manner hereinafter described and illustrated in the accompanying drawing in which:

30 Figs. 1 and 2 are, respectively, a plan view and a side elevation of a semi-tubular metal frame folding cot embodying my invention.

Fig. 3 is a cross sectional view at line 35 3—3 of Fig. 1.

Fig. 4 is a detail view in longitudinal section of one of the middle joints of the frame.

Fig. 5 is a detail in section at line x—x 40 of Fig. 4.

Fig. 6 is an elevation showing the frame folded.

Figs. 7, 8 and 9 are detail side, end and 45 sectional views respectively of the connection between the end legs and the frame.

Fig. 10 is a detail view of one end portion of one of the end bars.

Fig. 11 is a detail view of the top portion of one of the middle legs.

50 As shown in the drawing, the cot comprises a rectangular shaped frame which is composed of two pairs of side bar sections 1 and 2, which are formed of tubular metal. A pair of semi tubular metal legs 3 and 4 55 are connected by a pivot 5, approximately midway thereof, so that they will fold to

a position in which they are side by side and the upper ends of said legs are each provided with a connecting bar 6, which is formed of semi tubular metal. The end portion of each leg is inserted therein at the middle thereof, and at right angles thereto, and connected thereto by welding. The particular manner in which this connection is preferably made is indicated in the drawings, the end portion of the semi tubular metal leg being split and bent at right angles to form ears 7, which are convexly formed to fit against the concave inner surface of the connecting bar, said ears being 65 connected thereto by spot-welding. The middle portion of the leg is somewhat flattened and the adjacent side of the connecting bar is also flattened, so that the surfaces lie flat against each other and these portions are spot welded together, so that the 70 tubular legs and connecting bars are rigidly connected.

The opposite portions of the connecting bars 6 project equally at opposite sides of 80 the legs to which they are connected, and are formed of semi tubular metal of the same size externally as the size internally of the side bars 1 and 2, and said portions of the bars 6 are placed within the adjacent 85 end portions of the side bars so that said side bars will be held in exact alignment and their adjacent ends will be held in as close proximity as practicable. Pivot pins 8 are then inserted through the sides of the 90 side bars and connecting bars as thus arranged, as shown in Fig. 5, said pins being inserted adjacent the ends of the connecting bars, so that the side bars extend over the same towards the middle thereof for a substantial distance. The side bars are thus 95 positively limited against swinging movement beyond the aligning position, but are arranged to swing into parallel relation, as indicated in the dotted line positions of Fig. 4, the ends of the connecting bars being bent into rounded form about the pivot pins 8 as centers. The ends of the pins 8 are riveted, so that permanent connections are provided.

Two pair of end legs 10 and 12 are provided, which are similar in every respect to the legs 3 and 4, being pivotally connected at their middle portion, as shown in Fig. 3. The end portion of each leg 10 and 12 is also provided with a connecting bar 13 which is connected by spot welding in a manner simi-

lar to that already described with reference to the connecting bars 6. One end portion of each bar 13 is similarly formed to each end portion of the bars 6, and these end portions are pivotally connected to the opposite end portions of the side bars by pivots 14 in the same way as that already described with relation to the connection between the adjacent ends of the side bars and the connecting bars 6. The opposite end portions of the bars 13 are bent into substantially cylindrical form to provide posts 15, as shown in Figs. 7, 8, and 9, and semi tubular metal end bars 16 are provided, the end portions of which are bent to form sockets 17, which are adapted to fit closely on the post portions 15 of the bars 13. Folding braces 18 are connected to each end leg 10 and 12 and to the adjacent side bar sections 1 and 2, so that said legs may be locked in positions at right angles to the frame.

The bed canvas X is connected to the side bar sections in the usual manner, edge portions of the canvas being passed about said sections and stitched to itself to form loops, the portions opposite the middle joints being cut away to permit free action of the latter. End loops are also formed in the canvas through which the end bars 16 may be inserted, after which said bars may be placed on the posts 15, the latter entering the sockets in the ends of the bars 16, which thus act to stretch the canvas lengthwise and also act as spreaders to prevent the frame from collapsing. The canvas is cut away at its corners over the braces 18, as shown in Fig. 1 and for obvious reasons.

When the parts are in the position for use, shown in Figs. 1 and 2, the canvas will be tightly stretched lengthwise and crosswise of

the frame, which will be rigidly and firmly supported. In folding the cot, the end bars 16 will first be removed, then the braces 18 will be broken out and the side bars 1 and 2 will be swung together. The end legs will then be folded against the adjacent side bars by swinging relatively on pivots 14, and then the side bars will be swung relatively to the middle legs on pivots 8, so that the frame is compactly folded, as indicated in Fig. 6. 45 50

The form of joint employed between the legs and the frame is durable and strong and gives great rigidity to the frame when in position for use. The arrangement whereby the end bars are attached to the frame by the same means as that which is employed to connect the frame and end legs, is not only simple and convenient, but also provides means for connection of the end bars without increasing the length of the frame. 55 60

I claim:

A folding cot comprising side bars of semi tubular metal, a pair of pivotally connected legs at one end of said bars, a connecting bar rigidly connected to the upper end of each leg at right angles thereto and having one end portion fitted within the end portion of one of said side bars and pivotally connected thereto to permit relative swinging thereof between a position of alignment and a position at right angles, the opposite end portion of each connecting bar projecting beyond the supporting leg to form a post and an end bar having a socket in each end adapted to receive the posts of said connecting bars. 65 70 75

In testimony whereof, I have signed my name to this specification.

JULIUS L. CABLE.
